UNITED STATES PATENT OFFICE.

PHILIP FORSCHLER, OF NEW ORLEANS, LOUISIANA.

ENVELOP.

941,924.

Specification of Letters Patent.

Patented Nov. 30, 1909.

Application filed June 21, 1909. Serial No. 503,482.

To all whom it may concern:

Be it known that I, PHILIP FORSCHLER, a citizen of the United States, residing at New Orleans, in the parish of Orleans and 5 State of Louisiana, have invented new and useful Improvements in Envelops, of which the following is a specification.

My present invention pertains to envelopes; and it contemplates the provision of 10 a strong and safe envelop and one which is simple and inexpensive in proportion to the security it is calculated to afford.

The invention also contemplates the provision in an envelop of a peculiar closure, of 15 the metallic-fastener type, embodying such a construction that when the envelop is properly closed and subjected to exterior pressure, it is securely fastened and cannot be opened without mutilating the paper or 20 other material of which the envelop is formed to such an extent as to make it manifest that the envelop has been tampered with.

The invention further contemplates the 25 provision of an envelop embodying such a construction that when the envelop is properly closed and fastened, access cannot be gained to the interior of the envelop even when steaming is resorted to to separate 30 those portions of the envelop which I prefer in practice to connect together by adhesive material.

Other advantageous characteristics of the 35 invention will be fully understood from the following description and claims when the same are read in connection with the drawings, accompanying and forming part of this specification, in which :

Figure 1 is a plan view of the blank from 40 which the envelop is formed. Fig. 2 is an enlarged transverse section of the envelop, on line 2—2 of Fig. 3. Fig. 3 is a longitudinal central section of the same, on line 3—3 of Fig. 2. Fig. 4 is a perspective view 45 of the metallic fastener *per se* of the envelop.

Similar letters of reference designate corresponding parts in all of the views of the drawings.

50 The envelop is preferably made of one piece of paper, and, as best shown in Fig. 1, comprises a body A, an end flap B, side flaps D and E, tongues G, an end or closure flap I, and a supplemental side flap E³. 55 The end flap B is provided with slits b and

a keeper strap c between said slits b, and is also provided with slits d d' and a portion e intermediate the same. On the side flaps D and E and extending from the side edges of the bottom portion h of the end flap B 60 are bottom portions f and g. It will also be noted that said side flaps D and E are provided with slits i and closure portions j and k, the latter being arranged at opposite sides of and integral with the closure flap I. 65 The supplemental side flap E³ has a bottom portion p joined to the end of the bottom portion g and also has a shallow closure portion r arranged opposite and joined to the adjacent end of the closure portion k. 70 At m in the supplemental side flap E³ is provided an oblong aperture, designed to be registered with the aperture d' of the end flap B, the aperture l of the closure flap I, and the apertures d⁴ of the side flaps D and 75 E. The tongues G extend from the bottom portions f and g of the side flaps D and E. At this point I would have it understood that while I prefer to employ the supplemental side flap E³ for reasons which will 80 hereinafter be stated, the said supplemental side flap E³ is not essential to the successful practice of my invention, and therefore the said flap E³ may, when deemed expedient, be omitted without involving departure 85 from the scope of my claimed invention.

In making up my novel envelop from the blank shown in Fig. 1, the supplemental flap E³ is first folded inwardly against the inner side of the side flap E, and the portions g 90 and h thereof, after which the flaps E and E³ are folded inwardly against the inner side of the body A, so that the flap E³ rests between the flap E and the body A, and the bottom or lower end portion p of said flap 95 E³ rests between the portions g and h, while the portion r on said supplemental flap rests between the top portion k on side flap E and the closure flap I. The side flap D is then folded inwardly against the outer side 100 of the side flap E, and with that done it will be seen that the bottom portion f on said side flap D will rest against the bottom portion g of the side flap E while the closure portion j of flap D will rest against the outer side of the closure portion k of side flap E. The tongues G which are then opposed or arranged side by side, are then passed through the keeper strap c at the 105 inner side of the end flap B, after which the 110

5 tongues G are passed through the slits i in the side flaps D and E, preferably in the manner shown in Figs. 1 and 3, in order to enable the tongues to connect and hold the 10 said flaps D and E together. At the proper time the envelop is folded at t so as to superpose bottom portions h p g and f upon the outer side of the side flap D, and also at the proper time the tongues G are passed 15 outwardly through the slit d in the end flap B, which latter in the bag as made up is designed to rest at the outer side of the superposed end or bottom portions described and also at the outer side of the side flap D. 20 With the flaps and the tongues arranged as stated, relative to the body A, it will be manifest that a strong and durable envelop is formed, and one that is open at one end. The supplemental side flap E³ serves, as 25 clearly shown in Fig. 3, to cover the portions of the tongues G that otherwise would be exposed to the interior of the envelop, and is desirable and is preferably employed for that reason. The bottom portions h, p, g, 30 and f serve when folded upon the outer side of the side flap D, as before described, to prevent access being gained to the lower end of the envelop in the event that those portions of the envelop preferably connected by adhesive are subjected to a steaming or other surreptitious treatment.

It will be noted here that in the made up envelop, the side flap D is pasted to the outer side of the side flap E at such points as are 35 desirable, and that the end flap B is pasted similarly to the outer side of the side flap D; and pasting of the parts being preferably resorted to in order to lend additional security to the envelop, as well as to assure the parts 40 remaining in their proper relative positions until the envelop is put into use and the upper end thereof is closed and fastened.

As best shown in Fig. 4, the metallic fastener M comprised in my improvements 45 includes a flat body m' having a slot n' adapted to be registered with the aperture m in flap E³, the apertures d⁴ in the side flaps D and E, and the aperture d' in the end flap B. The fastener M also includes 50 arms or prongs p', and a keeper arm s' initially resting at an acute angle to the body m' and having an inturned hook t' which terminates in an end portion u' directed as shown. The said fastener M is arranged at 55 the inner side of the supplemental side flap E³, and is connected to the flap E³ and also to the flaps E, D and B, by the prongs or arms p' which are extended through the flaps and are bent against the outer side of 60 the flap B, as shown.

The envelop is closed by folding the flap and the closure portions j, k and r over the end flap B, and passing the apertured end portions of the tongues G, which are preferably pasted together to form a single tongue,

through the registered apertures in the several flaps and also through the slot n' in the fastener M. Pressure is then exerted on the flap B, whereupon the hook t' will be secured in the aperture of the tongues and the 70 tongues will be clamped between the arm s' and body m, Fig. 3. The inward folding of the portions j, k and r contributes materially to the secure closing of the upper end of the envelop.

75 The construction herein illustrated and described constitutes the best practical embodiment of my invention that I have as yet devised, but it is obvious that in the future practice of the invention such changes or 80 modifications may be made as do not involve departure from the scope of my invention as defined in the claims appended.

Having described my invention, what I 85 claim and desire to secure by Letters-Pat- ent, is:

1. An envelop formed of a piece of suitable material and comprising a body, an end flap, side flaps arranged between said end flap and the body and having slits, and a 90 tongue extending from one end of one side flap and through the slits of the side flaps and also through the end flap.

2. An envelop formed of a piece of suitable material and comprising a body, an end 95 flap provided with a keeper-strap, an opposite end or closure flap having an aperture, side flaps arranged between the first-named end flap and the body and having slits and also having registered apertures adapted to 100 be registered with the aperture in the second-named end or closure flap, and a tongue extending from one end of one side flap and passed through the keeper-strap of the first-named end flap and also through the slits 105 in the side flaps and adapted to be passed inwardly through the registered apertures in the closure flap and side flaps and to be secured within the envelop.

3. An envelop formed of a piece of suitable material and comprising a body, an end 110 flap provided with a keeper-strap and also provided with a slit and an aperture, an opposite end or closure flap having an aperture adapted to be registered with that of the 115 first named end flap, side flaps arranged at the inner side of the first-named end flap and having slits and also having registered apertures in the end flaps, a supplemental side flap carried by one of the side flaps and disposed between the same and the body and having an aperture registered with those of the side flaps and end flaps, tongues extending from the ends of the side flaps and passed through the keeper-strap of the first- 120 named end flap and also through the slits in the side flaps and then out through the slit in said end flap and adapted to be passed inwardly through the registered apertures 125 in the end and side flaps and supplemental 130

side flap, and a fastener secured within the envelop and adapted when pressed to engage and hold the said tongue.

4. An envelop formed of a piece of suitable material and comprising a body, a lower end flap, an upper end or closure flap having an aperture, side flaps arranged between the lower end flap and the body and having slits and registered apertures and also having lower 10 end portions *f* and *g* folded between the lower end flap and the outer of the side flaps, and further having upper end portions *j* and *k* adapted to be folded between the upper end or closure flap and the outer of the side

flaps, and a tongue extending from the lower 15 end portion of one side flap and through the slits of the side flaps and also through the lower end flap, and adapted to be passed inwardly through the registered apertures in the closure flap and side flaps and to be 20 secured within the envelop.

In testimony whereof I have hereunto set my hand in presence of two subscribing witnesses.

PHILIP FORSCHLER.
